MOISTURE REPELLING IRONING BOARD

Alva T. Smith, Milwaukee, Wis., assignor to The Sunlite Mfg. Company, Milwaukee, Wis., a corporation of Wisconsin

Application September 22, 1938, Serial No. 231,107

3 Claims. (Cl. 38—137)

This invention resides in novel ironing supports wherein the usual ironing board covering of fabric, such as muslin, is supported by the usual resilient textile or fibrous padding, which, however, in this invention is in turn supported by a moisture-impervious, heat-conducting, supporting surface provided with heat-supplying means for furnishing heat to said supporting surface at a temperature sufficient to accelerate the volatilization of moisture contained in said pad, but at a temperature low enough so that thermal decomposition and charring of said textile pad does not occur.

Heretofore, in the ordinary domestic ironing board, a rigid wood or metal supporting surface has been provided upon which there has been placed a resilient pad covered in turn by a muslin or like textile ironing board cover. The conventional process of hand ironing when performed on such a board is accompanied by a driving of moisture from the garment being pressed into the covering of the ironing board. Some of this moisture thus removed from the garment being pressed accumulates in the ironing board pad until the latter becomes distinctly moist. When this condition occurs, the ordinary process of hand ironing is perceptibly retarded because of the fact that moisture repeatedly emerges from the pad into the garment being pressed and must be repeatedly driven out again by the heat of the iron until the garment stays dry. Under these conditions the operator is under the necessity of applying the iron over protracted periods to the garment being pressed for the purpose of imparting sufficient heat to the pad to cause it to lose its excess moisture. This practice is time consuming and detrimental to the garment being pressed.

The pad of the ironing board of this invention, on the other hand, through the moisture-impervious, heated, supporting layer placed therebeneath, is continually maintained at a temperature favorable to the rapid relief of moisture. As a result, when a garment is ironed upon the ironing board of this invention, the moisture driven from the garment under the influence of the heat of the hand iron is but momentarily and temporarily retained in the resilient ironing pad and as soon as the hand iron is passed to other parts of the garment at other parts of the ironing board, the heat being supplied from beneath the pad causes the moisture in the pad to be driven out. Under these conditions a garment may be ironed much more expeditiously and ef-

fectively and with a minimum of frictional engagement with the hand iron.

This invention is herein described with the aid of the accompanying drawing which forms a part hereof and in which:

Fig. 1 is a plan view of a form of the ironing board of this invention made of metal.

Fig. 2 is a partial sectional elevation view taken at the plane 2—2 of Fig. 1.

Fig. 3 is a partial elevational section viewed at the plane 3—3 of Fig. 1.

There is shown in Figs. 1, 2, and 3 a board composed of an intermediate sheet of corrugated metal 53, in the corrugations of which there is placed heating element 54 comprising a resistance wire covered with heat-resistant insulation, such as asbestos. It will be noted from the drawing that transverse connections between the corrugations of sheet 53 are provided along the margin of the board to accommodate return bends 20 in the element. Beneath the intermediate sheet 53 is placed a corrugated sheet 55 to furnish transverse stiffness. The whole is then covered with a sheet metal cover sheet 56 to provide a smooth surface to support the usual resilient 25 ironing pad 57, which in turn is covered by the conventional textile ironing board cover 58. A thermostat of any suitable form, such as shown in dotted lines 59, may also be provided and electric power for element 54 may be supplied 30 through a junction box 60 and supply lead 61. The supply of heating current may also be regulated in well-known manner by properly proportioning the resistance of the element to the power supply available, or by providing a switch. 35

It may be seen from the embodiment of this invention above described that a combination of ironing pad and supporting structure is provided in which the supporting structure is adapted to drive moisture from the pad at an accelerated 40 rate. The heat is supplied on the side of the ironing pad opposite the side upon which the ironing itself is performed. The heat thus supplied beneath the pad is in no sense a pressing heat and in fact is maintained at a temperature 45 considerably below that of common pressing heat. This is necessary to protect the pad from charring and thermal decomposition. The heat supplied even at this moderate temperature is sufficient, however, to very materially accelerate the 50 rate of departure of moisture contained in the pad. A very substantial increase in the rate of hand ironing results therefrom. While any heat below the temperature of decomposition of the pad is advantageous so long as it exceeds normal 55

room temperature, I prefer to operate within the upper ranges of these temperatures. For example, beneficial results may be obtained by operating at 150 degrees Fahrenheit and a marked 5 increase may be noted without any detrimental effect upon the pad as the temperatures are increased upward toward 210 degrees Fahrenheit. In the case of a woolen pad, the temperatures may be carried even higher, but an upper limit 10 for most textile materials will be experienced between 200 and 250 degrees Fahrenheit.

The junction box shown in Fig. 1, may conveniently be supplied with a plug-in receptacle to which the hand iron may be attached and in 15 such event having but one cord from the ironing board to the wall is of great convenience to the operator, as it allows full use of the iron cord while covering the area of the work to be done.

While this invention has been herein described 20 with reference to a specific embodiment thereof, it is not intended that the protection of Letters Patent granted hereon be unnecessarily restricted thereby, but that such protection shall extend to the full scope of the advance of the 25 art represented within his disclosure and contained within the scope of the claims hereto appended.

What I claim as my invention and wish to secure by Letters Patent is:

30 1. In a moisture-repelling ironing board, the combination comprising a light-weight sheet metal supporting base of ironing board shape with a tapering end and having a plurality of substantially parallel corrugations running 35 lengthwise thereof for imparting stiffness thereto, transverse corrugations between said longitudinal corrugations disposed along and within the margin of said base and spaced both laterally and longitudinally with respect to one another 40 along the margin of the tapering end of said base to approximate the tapering outline thereof, said transverse corrugations forming communicating passages near alternate ends of adjoining pairs of said parallel corrugations providing a continuous back and forth passage for 45 a continuous electrical-resistance-heating conductor across the upper face of said base, an insulated electrical resistance-heating conductor disposed within said passage, and a substantially 50 flat sheet metal covering plate superimposed upon and united with said supporting base adapt-

ed to hold said conductor in place and to furnish a flat surface for support of an ironing pad.

2. In a heatable board of the class described, the combination comprising a light-weight sheet metal supporting base of ironing board shape 5 with a tapering end and having a plurality of substantially parallel corrugations for imparting stiffness thereto, transverse corrugations between said parallel corrugations ranged along and within the margin of said base and spaced 10 both laterally and longitudinally with respect to one another along the margin of the tapering end of said base to approximate the tapering outline thereof, said transverse corrugations forming communicating passages near alternate 15 ends of adjoining pairs of said parallel corrugations, thus providing a continuous passage for a continuous electrical-resistance-heating conductor, an insulated electrical-heating-conductor disposed within said passage, and a substantially flat sheet metal covering plate superimposed upon and united with said supporting base 20 adapted to hold said conductor in place and to furnish a flat surface for support of an ironing pad. 25

3. In a moisture-repelling ironing board, the combination comprising a light-weight sheet metal supporting base of ironing board shape with a tapering end and having a multiplicity of 30 parallel ranged deformations distributed over the surface thereof for imparting stiffness thereto, a multiplicity of transverse deformations between said parallel ranged deformations disposed along and within the margin of said base 35 and spaced both laterally and longitudinally with respect to one another along the margin of the tapering end of said base to approximate the tapering outline thereof, said transverse deformations forming communicating passages near alternate 40 ends of adjoining pairs of said parallel ranged deformations thus providing a continuous passage for a continuous electrical-resistance-heating conductor, an electrical-resistance-heating conductor disposed within said passage, and a substantially flat sheet metal 45 covering plate superimposed upon and united with said supporting base adapted to hold said electrical-resistance-heating conductor in place and to furnish a flat surface for support of an 50 ironing pad. 50
